CLAIM

The ornamental design for a desk, as shown and described.

DESCRIPTION

1. Desks

1.1 : Front

1.2 : Back

1.3 : Right

1.4 : Top

1.5 : Bottom

1.6 : Cross-sectional

A left side view of design 1 is omitted because it is a mirror image of the right side view; the parallel thin lines on the surfaces of the desk represent only shading and do not illustrate ornamentation or decoration; the parallel lines on the sectional surfaces represent only hatching; the reproduction 1.6 is a cross-sectional view vertically sectioned at the center of the desk.

Throughout the Figures, the parts shown by means of broken lines are not part of the claimed design.
